HIGH VOLTAGE ELECTRODE HOUSING

Samuel C. Miller, Manhattan, N. Y.

Application January 20, 1936, Serial No. 59,891

5 Claims. (Cl. 173—328)

This application relates to insulators; more particularly to high voltage electrode housing insulators including contact mounts for neon tube signs.

5 In the mounting of an assembly of neon tube signs or similar decorative signs in which the parts are exposed to the atmosphere, the contact portions adjacent the tube electrodes are mounted within insulator sockets of deep cup-shaped 10 construction which are affixed to a supporting body, usually of metallic frame work, to which the ground connection of the electrical system is connected. This insulator carries terminal contacts to which the electrode contacting portion of 15 the neon tube is assembled. By reason of exposure to the weather, not only is it essential to include insulating material of high dielectric strength, but also the insulator must include means for the drainage of accumulated moisture 20 and rain water.

Where I have utilized porcelain insulators for the purposes contemplated by me, the improvisation of the contour permitting the inclusion of drain holes for accumulated moisture and rain 25 water is a comparatively simple problem.

However, where I have employed so-called porcelain insulators, the general porosity of porcelain in the presence of the high intensity current employed makes this material objectionable 30 in its use for the purposes above referred to.

While glass, specifically, the Pyrex type glass or that of boro-silicate composition, provides an excellent insulator of proper dielectric qualities and density or freedom from porosity, its 35 use for purposes contemplated by me was not commercially feasible, due to the inability to provide such essential details as proper insulating support of sufficient mechanical rigidity, as well as the drainage orifices which make continued 40 operation under inclement weather conditions possible.

My invention makes possible the use of the Pyrex type or boro-silicate type of glass, as an 45 insulator and terminal support which combines high electrical insulating qualities, as well as the mechanical function of supporting the terminal, while providing the necessary drainage facilities for moisture and water which is important in an outdoor tube sign construction.

50 For a clearer understanding of my invention, it may be noted that the utilization of glass, particularly the Pyrex type or boro-silicate type of glass, is advantageous in that the glass may be cast in molds, utilizing a plunger type of core.

55 The temperatures at which glass of this character is cast prohibits the use of small sized cores in order to form drainage orifices in the casting and which may remain in contact with the glass for any appreciable period of time, 60 with the molten glass at the high temperatures

employed. This is due to the fact that the material of the cores of small dimensions which must be utilized to form drainage orifices quickly deteriorates in the presence of the molten glass and limits the use of these molds, to make glass 5 casting commercially impractical.

It is therefore an object of my invention to provide an insulator construction and terminal mount which will make glass, particularly the Pyrex or boro-silicate type of glass commercially 10 available for insulator purposes, particularly in the formation of insulators and terminal mounts of the character contemplated by me for neon tube lighting purposes.

To attain the aforementioned objectives and 15 such other objectives as will be apparent or more clearly appear as this description proceeds, I make reference to the accompanying drawing forming a part hereof, in which—

Figure 1 is a longitudinal sectional view 20 through my electrode and terminal mount, showing a fragment of the housing to which the electrode is attached;

Figure 2 is a section taken on the line 2—2 of 25 Figure 1;

Figure 3 is a side elevation and fragmentary sectional view of my electrode blank at one stage of its manufacture.

Making reference to the drawing, Figure 1 illustrates a fragment of a neon sign frame 10, 30 having an orifice 11 through which a deep cup-shaped electrode housing or insulator 12 arranged to be exposed to the weather is disposed, so that a flange 13 abuts the outer face of the plate 10, and cooperates with a screw-threaded 35 collar 14 engaging the screw-thread 15 on the electrode housing 12 to bind the same to the plate.

This form of connection is more or less standard and of well-known design.

In connection with an insulator of this general type, it will be observed that there is provided a central boring 16 exposed to the weather, through which the end of the neon tube sign carrying the electrode generally shown at 17 in dotted lines, passes. As atmospheric moisture 45 and rain water and the like may enter this boring, drainage must be provided by suitable orifices.

In attempting to provide drainage orifices in porcelain insulators, no difficulty has been experienced, but the type of insulating material is prohibitive for efficient operating conditions.

Accordingly, the insulator as contemplated by me to serve as a mount for a terminal in a neon tube construction, uses insulating glass of a Pyrex 5 type or boro-silicate glass composition. Accordingly, the body of the electrode 12 terminates adjacent the end, with an inwardly directed flange 17, the walls whereof define the enlarged orifice 18.

The enlarged orifice thus provided not only serves as a drainage orifice for the purposes previously emphasized but also serves to support the electrode contact and terminal post portion of the electrical circuit.

In Figure 1, I have shown a helical resilient spring contact 19, attached to the head 20, of a terminal post which is provided with a square shank 21 fitting within the cross-member 22 and 10 rests against the inner wall 23 of the flange 17. To the outer face 24 of the flange 17, there is applied the spider 25 with a screw-threaded orifice 26 engaging the shank of the post and rigidly holds the post in the axial position.

15 It will be observed that from this construction, the electrode contact 19 is given proper insulating assembly while providing a drainage orifice, thus combining mechanical rigidity, electrical insulation and drainage features. The construction as provided makes possible the use of glass, particularly the Pyrex type or boro-silicate glass 20 type of material for insulating purposes, in an insulator for the uses contemplated by me.

25 For a clearer understanding of the method of production of the insulator, reference will now be made to Figure 3, showing the general configuration of a die cast plunger core type of blank which is convenient for forming the final insulator with the orifice for drainage purposes, as previously 30 described.

The insulator in the form of a deep cup-shaped vessel having a central boring 16 is die cast with a bottom 30 and exterior offset shoulders 31 and an interior shoulder 32. The core plunger which 35 outlines the boring 16 may include provision for forming the lugs 22a.

40 This type of glass casting embodies the minimum use of heat resistant material and extreme simplicity of core outline, so that the mold and the core plunger may be used repeatedly without erosion, warping, burning or disfiguration of the mold and the core plunger.

45 After completion of the blank as shown in Figure 3, the bottom and offset portions 30 and 31, respectively, are ground off along the line x—y, to thereby provide the face 24, as shown in Figure 1. This operation thereby provides the orifice 18 without the need of boring or drilling the glass.

50 It will thus be observed that the nature of the configuration of the insulator blank shown in Figure 3 is readily adaptable for die casting and plunger-core operation, permitting the use of glass for insulator purposes in a device of the character contemplated by me. Whereas the 55 need for orificing the insulator would ordinarily make glass unavailable for the production of high voltage electrode housing for neon tubes, my construction makes such use of glass commercially feasible.

60 It will also be observed that I have provided a high voltage electrode housing or insulator for the purposes contemplated by me which combines efficient insulating qualities with rigidity and simplicity of construction, having utility elsewhere where these features are desirable as will be 65 readily understood by those skilled in the art.

70 While I have preferably shown the orificed portion 18 formed in the bottom of the electrode housing 12 as the most preferable form with the type of casting operation described it will be understood that to some extent the location of the flange outlining the orifice for drainage and for mounting the contact and terminal may be posi-

tioned elsewhere for different forms of electrodes and casting operations for these forms.

It will also be observed that though my form of electrode housing or insulator has preferred use for insulators made of glass, the assembly described by me has novelty of general utility for other insulator materials, and of broader scope coming within the purview of the appended claims.

Having thus described my invention and illustrated its use what I claim as new and desire to secure by Letters Patent is—

1. A high voltage electrode housing of insulating material having an enlarged orifice for drainage when used for purposes described, cross-members spanning said orifice, and supporting an electrode contact and terminal disposed through said orifice, said cross members, contact and terminal obstructing only a portion of said orifice, leaving substantially one-half the area of the orifice for drainage.

2. A high voltage electrode housing of insulating material for the purpose set forth, comprising insulator glass formed with an inwardly directed flange adjacent to one end thereof defining a drainage orifice, cross bars disposed on opposite faces of said flange, and a terminal post for clamping said bars in position and supporting an electrode contact, said cross bars, post, and contact obstructing only a portion of said orifice and leaving a substantial passage for drainage.

3. A high voltage electrode housing of insulating material for the purposes set forth, comprising insulator glass formed with an inwardly directed flange adjacent one end thereof, defining a drainage orifice, a terminal mounting and contact support maintained within said orifice, and cross members spanning said orifice and supporting said terminal mounting, said cross members obstructing only a portion of said orifice and leaving a substantial passage for drainage.

4. A high voltage electrode housing of insulating material for the purpose described comprising a cast insulator of heat resisting boro-silicate glass formed with an inwardly directed flange at one end thereof and continuous with the end of the side walls thereof, said flange defining a drainage orifice and constituting means for mounting a terminal and a support for a contact within said orifice in association with cross members spanning said orifice for supporting said terminal mounting and contact support and in which said cross members obstruct only a portion of said orifice, leaving a substantial passage for drainage.

5. In a high voltage electrode housing assembly for the purposes set forth, a housing of insulating material and which has an inwardly directed flange adjacent one end thereof defining a drainage orifice and constituting means for suspending a terminal mounting and contact support, maintained within said orifice by cross members spanning said orifice and supporting said terminal mounting, with said cross members obstructing only a portion of said orifice, leaving a substantial passage for drainage, said housing being formed of cast insulating and heat resisting glass, the inwardly directed flange being continuous with the end of the side walls of the 70 housing.

SAMUEL C. MILLER.
